FULL-FASHIONED STOCKING AND PROCESS
OF PRODUCING THE SAME

Emilio Doura, Buenos Aires, Argentina

Application November 30, 1945, Serial No. 631,982

2 Claims. (Cl. 66—187)

1

This invention relates to an improved full fashioned stocking and to a process of producing it and is herein illustrated in some detail as embodied in a woman's stocking and a process for making it whereby the manufacture of such stockings is simplified and the quality improved and the resistance to wear is also improved.

According to the present invention it is no longer necessary to manufacture women's stockings on two different and separate flat-bed knitting machines, namely the machine that produces the leg, called the legger, and the machine that produces the foot, called the footer. According to the present invention the legger may do the complete work of knitting both the leg and the foot in a single operation of which the advantages will hereinafter appear.

In the ordinary process of knitting a stocking on the two machines, the legger and the footer, the transfer of the stitches from one machine to the other makes it almost impossible to get a perfect match of stitch and color between the silk that was knit in the leg and that which is knit in the foot. The transfer of stitches from the needles of the legger machine to the needles of the footer machine is called topping and that topping causes the difference in the shade and the shape of the fabric in the finished stocking. Moreover, during the operation of transferring the stitches of the leg portion to the foot machine, there is great likelihood of dropping a stitch or of a stitch running with the result that many stockings are damaged and second quality hosiery is produced.

According to the process of the present invention, these inconveniences are avoided. The leg part and the foot part are knitted continuously on the legger machine in such a way that when the operation has reached the lower edge of the high spliced heel the proper setting of the yarn carriers starts the formation of a rectangular fabric on each side of the stocking omitting the reinforcement from the stitches which had been incorporated in beginning the knitting of the high spliced heel.

This rectangular fabric knitted only with the leg portion yarn is continued for 8 or 10 courses with a width a few needles narrower than the width of the splicing at that part of the stocking so that the stocking fabric is reinforced by those few needles adjacent the usual leg portion yarn fabric.

Then the carriers of the reinforcement yarns are put back into operation and the knitting of the reinforced splicing is resumed at the full width of the original reinforced area.

2

After knitting about 4 courses of this reinforced fabric, a course of loose yarn stitches of leg yarn material free of the reinforcing is produced on both sides of the stocking the same width as the width of the rectangular unreinforced stitches mentioned above. Following this course the knitting of the stocking with reinforced stitches is resumed to form the instep, sole and toe. These 4 courses of reinforced fabric between the unreinforced area and the course free of the reinforcing prevents the running or falling of the stitches when the sides are cut at a line which will be described in detail below.

According to this invention it is possible to produce a foot blank wider on the lower portion of the leg blank, thus providing a wider fabric which fits the circumference of the women's feet in a more comfortable manner and preventing the tensions and stretches which ordinarily produce premature breakage.

This production of a wider foot blank is obtained by permitting the yarn carriers which are knitting the unreinforced rectangular fabric to work successively on a wider range of needles. To accomplish this the carriers are preferably mechanically combined with the narrowing mechanism of the leg knitting machine in such a way that at every second course the yarn carriers displace two needles outwardly on each side. The unreinforced area according to this phase of the invention is no longer rectangular but of irregular shape, the width of the fabric being many needles wider than at the starting point so that it is possible to obtain a wider foot part, better suited to produce wearing qualities.

The stocking so produced in both forms lacks the heels which are hitherto applied separately on an auxiliary machine called a heelng machine. According to the present invention this producing of heels is effected on the footer machine which with some slight modification produces the required heel tabs.

The present invention makes it possible to utilize the footer machine by transferring the stockings from the legger to the footer by catching the stitches of the last or next to the last reinforced course of the high heel on combs or on bars provided with pointed needles along each end, there being as many needles as the width of the heel to be knitted. The sides of the stocking are preferably caught on said needles at the line where the first unreinforced course starts. The bars are placed at the footer machine and the stitches transferred to its needles so that the heel is started as a continuation of the high heel.

After the heels are produced in this way the

stockings are taken to a looping machine where the inner selvedge of the heel tabs is linked or looped to the loose course of stitches free of the reinforcement mentioned above.

In the accompanying drawings:

Fig. 1 shows a fragmentary leg and foot as it comes from the legger machine.

Fig. 2 shows the stocking after the heels have been knit on the footer machine.

Fig. 3 shows the foot being knitted wider than the leg.

Fig. 4 shows the same after adding the heels.

Fig. 5 shows a finished stocking.

The leg part of A of the stocking in Fig. 1 continues without interruption forming part B which becomes the instep of the foot but on each side of the stocking the high heels H are knit with the leg yarn plus a reinforcing yarn. The yarn carriers providing these reinforcing yarns are thrown out of operation so that the leg yarns knit the unreinforced rectangular area E for about 10 courses so that adjacent the instep a few needles knit in the reinforcement but most of the reinforcing is omitted.

After the 10 unreinforced courses are knit a single course of stitches a is knit with the leg yarns alone, free of the reinforcing yarns, usually about 4 courses below the 10 unreinforced courses mentioned above.

After knitting the stitches a, knitting is continued normally to make the instep B, the reinforced sole S and the reinforced toe T.

The stocking blank so produced on the legger machine is transferred to or topped onto a comb which has pointed needles near each of its ends, said needles being sufficient to provide the width of the heel to be knitted. This transferring or topping is effected on the last course or the next to the last course f of the high heels H in Fig. 1 by the needles of a topping stand and the rectangular sections E are cut at their upper edge e, thus permitting the foot part of the stocking to fold over and backward. The cut stocking is transferred to the topping bars so as to render possible the placing of this topping bar with its stocking on the needles of the footer machine and on that machine knitting the heel tabs that appear on Fig. 2.

To facilitate this operation the footer machine may have its central needles, sinkers and dividers removed in the central section while knitting the heel tabs for each stocking. The knitting of the heel tabs proceeds normally after adjusting the yarn carriers and setting them at the required width of the heel.

It will be noted that by first severing the stocking at the lines e, e in Fig. 1 and then knitting the heels it became possible to do away with the need of the special flat knitting machine called the heeling machine.

The portions E, E of Fig. 1 make it possible to cut the unreinforced lines e, e, thus permitting the foot of the stocking to be folded backwardly leaving the stitches on the lines f, f free to knit on a footer machine.

The stocking with the wider foot illustrated in Figs. 3 and 4 is made by the same procedure except that when the high heels have been finished and the unreinforced areas E¹, E¹ are started, the carriers in knitting the 10 courses of this area begin displacing outwardly to pro-

duce the trapezoid-shaped unreinforced area with an inclined outer edge w, w.

To obtain this the carriers of the narrowing mechanism are so adjusted that the carriers slide out at each one or two courses 2 needles on each side of the stocking. This widening of the foot is possible according to the present invention because the fabric E¹, E¹ is cut simultaneously with the linking operation and the inner edges of the heel tabs are knitted first to the edges b', c' of the narrow reinforced zone forming a continuous linkage or seam forming the angular corner of Fig. 5.

After knitting the leg blank of Fig. 3 the heels are knit as those described above and a stocking blank like Fig. 4 is produced. This blank is taken to a linking machine where the edges c¹, c¹ of the heels are joined with the lines a¹, b¹ producing the stocking of Fig. 5.

Having thus described certain embodiments of the invention, what is claimed is:

1. The process of producing a stocking for women which includes knitting yarn to form a leg part, continuing knitting the yarn to form a foot including knitting reinforcing yarns along each edge, said edge including an unreinforced widening zone of about ten courses of leg yarn and a narrow reinforced zone of said ten courses between the reinforced area and the front of the foot, cutting the unreinforced zones, transferring the stocking to the needles of a footer machine, knitting the heels on said machine, linking the inner edge of each heel to the edge of said narrow reinforced zone to form a short seam, and thereafter linking the remainder of the heel edge to the reinforced edge at the bottom of the unreinforced zone to continue the short seam at another angle, and form a topping corner with it.

2. A stocking for women including a knitted yarn leg part, a foot part knitted with said yarn plus knitted-in reinforcing yarns along each edge, said edge including an unreinforced widening zone of about ten courses of leg yarn and a narrow reinforced zone of said ten courses between the unreinforced area and the front of the foot, a heel knitted to the edge of the severed unreinforced zone and also knitted to the edge of each said narrow reinforced zone and further linked to the short reinforced edge left at the bottom of the several unreinforced zone so as to continue beyond the short edge to continue the short seam at another angle and form a topping corner with it.
